(57) **CLAIM**

We claim the ornamental design for an implant for bone fixation, as shown and described.

DESCRIPTION

FIG. 1 is a perspective view of an embodiment of the claimed design;

FIG. 2 is the perspective view thereof shown with a screw inserted therein;

FIG. 3 is a top view thereof with two screws inserted therein;

FIG. 4 is a top end view thereof;

FIG. 5 is a side view thereof; and,

FIG. 6 is a bottom end view thereof.

The ornamental design which is claimed is shown in solid lines in the drawings. The broken lines in the drawings are for illustrative purposes only and form no part of the claimed design. Broken lines formed by equal length dashes show unclaimed subject matter.
